(57) **CLAIM**

The ornamental design for storing station for roll containers, as shown and described.

DESCRIPTION

FIG. 1 is a side elevational view of a storing station for roll containers showing my new design;

FIG. 2 is a bottom perspective view thereof;

FIG. 3 is a top right side perspective view thereof;

FIG. 4 is a top left side perspective view thereof;
FIG. 5 is a side elevational view of a second embodiment of the present invention;

FIG. 6 is a top left side perspective view thereof;

FIG. 7 is a top right side perspective view thereof; and,

FIG. 8 is a bottom left side perspective view thereof.
